UNITED STATES PATENT OFFICE.

FRANK C. SCHMITZ, OF NEW YORK, N. Y.

ELECTRIC FURNACE.

1,226,264.

Specification of Letters Patent. Patented May 15, 1917.

Application filed November 3, 1913. Serial No. 798,922.

To all whom it may concern:

Be it known that I, FRANK C. SCHMITZ, a citizen of the United States, residing at New York, in the county of New York and 5 State of New York, have invented new and useful Improvements in Electric Furnaces, of which the following is a specification.

My present invention relates to certain new and useful improvements in electric 10 furnaces of the water-cooled type, and more particularly to furnaces especially designed for reducing or melting phosphate rock in the production of phosphoric acid, although furnace structures built in accordance with 15 the present invention will be found to be serviceable in the treatment of other materials, especially where high heat is required to effect reduction.

Much difficulty has been experienced and 20 many failures have resulted from the attempts heretofore made to use known constructions of furnaces in the treatment of phosphate rock to produce phosphoric acid P_2O_5 gas, owing largely to the chemical action 25 of the highly heated molten material and slag upon the furnace walls, especially when the phosphate rock is melted in the presence of silicious material. It has been demonstrated under actual working conditions 30 with a mason-work furnace lined with silica and other fire-brick, that the furnace lining as well as its thick walls are soon eaten away and totally destroyed by the chemical action thereon of the molten mass within the 35 furnace, the life of the furnace being of comparatively short duration. Attempts have been made to provide a furnace with a metallic water-cooled pot, but these, so far as I am aware, have not proved entirely 40 successful owing to certain structural defects, such for instance as inefficient provision for proper circulation of the cooling medium, inability to remove and repair or replace a defective or burned-out water- 45 cooled pot; and liability of short circuits between the electrodes and metal parts of the water-cooled pot resulting in destruction of the latter and of the entire furnace structure.

50 One object of the present invention is to provide a furnace structure of simple construction, built upon scientific lines and pos-

sessing the necessary strength and durability to withstand the destructive influences arising during operation.

55 A further object of the invention is to provide a novel and simple construction of water-cooled slag-pot, cooling of the pot being effected through the medium of a plurality of independently insertible and removable water-cooled units, the purpose being to provide a water-cooled wall structure made up of independent water-cooled units any one of which may be removed at will, as in case of a defect appearing or developing, and a new unit substituted therefor, without disturbing the remainder of the furnace structure and without shutting down the reducing operation.

60 A further object of the invention is to provide novel and simple means for supporting the separate water-cooled units whereby they may be easily and quickly removed and replaced.

65 A still further object of the invention is to provide a novel and simple construction of furnace superstructure constructed of steel and concrete on scientific principles.

70 Another object of the invention is to provide a furnace structure of the character described with water cooled means for separately tapping therefrom different slag formations.

75 Another object is to provide a novel construction and arrangement of water-cooled jacket for the electrodes.

80 With these and other more or less important objects in view, the invention resides in the features of construction and novel combinations and arrangement of parts herein shown and described and then 85 more definitely pointed out in the claims.

85 In order to enable others skilled in the art to understand, construct and operate furnaces built according to the present invention, I will now proceed to describe the same in detail, reference being made for this purpose to the accompanying drawings wherein I have illustrated a preferred embodiment of the invention, and wherein:— 90

95 Figure 1 is a front elevation of a furnace constructed in accordance with the present invention, the slag-pit being shown in vertical section.

Fig. 2 is a vertical longitudinal section.

Fig. 3 is a part transverse section and part rear elevation.

Fig. 4 is an enlarged detail view partly 5 in section and partly in elevation of one of the water-cooled plates or units, showing the means for supporting the same in position, and showing also the inlet and outlet pipes for the cooling medium.

10 Fig. 5 is a view in vertical section of the water-cooled jacket for the electrodes.

Fig. 6 is a perspective view of the metallic superstructure for the furnace.

15 In the present embodiment of the invention I have shown a furnace construction wherein only a single pair of electrodes is employed, but it will be obvious that the same construction may be employed in connection with furnaces having more than one 20 pair of electrodes, the showing here being merely by way of example.

The foundation for the furnace may conveniently consist of a pair of spaced concrete walls 1 upon the upper face of each 25 of which may rest a wooden beam 2 preferably consisting of oil treated timber, this being for insulating purposes. At its front the furnace is preferably provided with a concrete slag pit 3 into which the molten slag 30 from the furnace may flow, the pit containing water in order that the hot slag may be immediately cooled and disintegrated upon its discharge into the pit.

35 The furnace super-structure consists in the instance shown of a pair of I-beams 4 of inverted arch or cradle form, one resting upon each of the spaced walls 1. Each cradle beam is supported by a pair of upwardly and inwardly extending supporting 40 posts 5 which preferably consist of I-beams, each post being secured at its upper end to one of the upper ends of the cradle beam by means of angle plates 6 and the said posts being secured at their lower ends 45 to the wooden beams 2 by means of lag screws as more clearly shown in Fig. 3. The cradle beams 4 rest upon the wooden beams 2 and these cradle beams are further supported by means of metal feet 7, each 50 riveted at its upper end to the cradle beam, and secured at its lower end to the wooden beam 2 by means of lag screws.

55 The top or upper wall 8 of the furnace is preferably constructed in the form of an arch made of silica or other fire-brick, the said arch being supported at its opposite ends upon the web portions of a pair of horizontally arranged I-beams 9, which I-beams rest upon the posts 5 and are secured 60 in position by means of the angle plates 6 that connect the cradle-beams with said posts.

Each of the upright posts 5 at the front of the furnace has attached thereto near its 65 upper end a step bracket 10, upon which

step brackets is supported a transversely arranged I-beam 12, extending across the front of the furnace upon which is built the upper front wall 13 of the furnace, which wall preferably consists of fire-brick. 70 I prefer to cover this front wall as well as the arch of the furnace with metallic sheathing plates 14 and 15, the sheathing plate 14 that covers the upper front wall 13 being riveted along its lower edge to the upper 75 flange of the transversely arranged I-beam 12, all as more clearly shown in Figs. 1 and 2.

The bottom and side walls of the furnace, which walls constitute the support for the slag pot are curved, that is, in the instance shown, they are made on curvilinear lines conforming to the shape of the cradle beams and supported by the latter. This curvilinear wall consists of a plurality of regularly spaced supports shown as consisting of I-beams 16 extending longitudinally of the furnace, that is, they are substantially parallel with the elements of the curved wall, and each beam rests at its opposite 90 ends upon the pair of cradle beams and is secured thereto by rivets. Each of the said I-beams 16 is partially embedded within a body of concrete 17 forming a reinforced concrete beam, the inner flange being embedded, and the lower flanged portion of each beam being exposed for a purpose presently to appear.

The spaces or cells between the reinforced concrete beams are of uniform length and 100 width and insertibly and removably supported in each of said spaces is a hollow water cooled plate or unit 18, which plates or units serve to maintain the furnace wall sufficiently cool to prevent destruction thereof and of the slag pot during the operation 105 of the furnace.

The water cooled plates or units 18 are removably supported in position between the spaced concrete beams 16 referred to 110 by means of steel yokes 20, which yokes extend transversely of the units and rest at their opposite ends upon the exposed flanges of the I-beams 16, as more clearly shown in detail in Fig. 4, the water cooled units being moved forwardly to be seated and securely held in position by means of wedges 21 driven between the said yokes and plates, as more clearly shown in said figure. It will thus be noted that each yoke 115 20 engaging with the flanges of the adjacent I-beams 16 constitutes a positive means for locking the water-cooled unit in its cell, as contradistinguished from merely holding the unit in place by the frictional engagement of the walls of such unit with the walls of the cell. Furthermore, such locking means is independent of the cell itself so that it may be readily manipulated to retain the cell in position or release the 120 125 130

latter when desired. It will also be seen that by the employment of the wedges 21 the water-cooled units may be positively forced inward to the desired position. The 5 yokes therefore, constitute means for removably supporting the cooling plates or units in position between the beams so that any plate or unit may be removed at will in case a defect is shown or develops, and 10 a perfect unit substituted therefor. This is a matter of great advantage and importance because the substitution of one plate for another may be made without shutting down the operation of the furnace and furthermore any unit may be added or removed 15 without disturbing any of the other units and also without in any way altering or tearing down any part of the superstructure or any part of the furnace walls. Repairs may thus be easily and quickly made 20 and at a minimum cost.

I prefer to make and arrange the cooling plates or units 18, in alined pairs as more clearly shown in Fig. 2, and between each 25 of the pairs of units I provide a reinforced concrete cradle or band 22, that follows the general contour of the bottom and sides of the furnace, the reinforcing means consisting of straps or rods 23, connected at their 30 opposite ends to the longitudinally extending beams 16, as more clearly shown in Figs. 2, 3 and 4.

The rear wall of the furnace, as more 35 clearly shown in Figs. 2 and 3 is constructed substantially like the bottom and side walls and consists of a plurality of regularly spaced transversely arranged truss-beams 24, each partially embedded in concrete 25, there being also vertically arranged concrete 40 connecting blocks 26, between adjacent beams as more clearly shown in Fig. 3, to provide cells or spaces for the removable rear-wall cooling-plates or units 18^a, which units are removably supported by the yokes 45 20^a, and wedges 21^a similar to those heretofore described. It is possible therefore to remove at will, for replacement or repair either of such rear-wall cooling units without disturbing any of the others and without tearing 50 down any part of the superstructure or the walls of the furnace.

The front wall of the furnace as more 55 clearly shown in Figs. 1 and 2 is constructed substantially like the rear wall just referred to in so far as its truss beams 24, and cooling plates or units 18^a are concerned, and these parts need not therefore be further described.

I prefer to line the inner, bottom, side and 60 end walls of the furnace chamber with metal plates 27, joined at the angles by means of angle irons 28, as shown in Fig. 2. The slag pot 29 of the furnace consists of a cementitious composition consisting of a mixture of ground slag and cement, the latter forming 65 about 5% of the mixture. The slag em-

ployed is preferably that resulting from the melting or reducing of phosphate rock and silica. This material I have found to be admirably suited to the purpose because it does not appear to deteriorate appreciably by 70 the reducing or melting operation, since it contains practically no phosphoric acid or silica and the fresh rock and silica fed into the furnace does not, therefore, attack the same, as it does in cases where the slag pot 75 consists of silica brick. This cementitious mixture of slag and cement is spread several inches thick around the inner walls of the furnace chamber and is applied with a trowel when in plastic form.

In order to tap the molten slag and phosphorus iron from the furnace, I provide in the front wall thereof, two water-cooled tap-spouts, one indicated by the numeral 30, being located at or near the bottom of the slag-pot 29, and projecting through its wall 80 as well as through the front wall of the furnace, and the other spout 31, being located above the spout 29, as more clearly shown in Figs. 1 and 2. There is a downwardly 85 inclined slag chute 30^a extending outward below the spout 30, and a similar chute 31^a arranged below the spout 31. These are for separately conveying the molten slag 90 into the slag pit 3, as it flows from the slag pot so that the different slags may be tapped off separately, both being marketable products, the one being "phos iron" and the other a silicious slag that may be employed in the manufacture of bricks or ground and used 95 as a fertilizer filler or otherwise employed.

Each of the tap spouts 30 and 31 consists of a double walled shell preferably made of bronze or a composition in which bronze predominates, and each is preferably of 100 frusto-conical shape. These tap spouts are water cooled, the cooling water entering the spouts through inlet pipes 32 and 33 respectively, said pipes being pipe-connected to a water main 34 common to both spouts. I 105 prefer to lead each inlet pipe 32 longitudinally through the hollow tap spouts with its inner end terminating at a point slightly removed from the smaller end of its spout so that the cooling water will enter the spout 110 at its inner or hottest point. The cooling water is led off from each tap spout by means of an outlet pipe 35 secured to the forward end of each spout, each outlet pipe having a 115 downturned end arranged directly above the 120 slag chute associated with its spout, so that the outflowing water will serve to cool the slag as it flows out through the spout.

In melting or reducing phosphate rock and silica combined to form phosphoric acid, 125 there is formed in addition to the slag a certain amount of what is known as "phos iron" and this being the heavier collects in the bottom of the slag pot. The phos iron is tapped off through the lower tap spout 30 and the 130

phosphate slag is tapped off through the tap spout 31. The tap spouts are usually closed by means of a suitable plug, and these may be removed at will to draw off either the phosph iron or the phosphate slag.

The object in melting or reducing the phosphate rock and silica is to drive off the phosphoric acid which is eliminated in the form of a gas or fumes. These are conducted to a tower (not shown) where they are sprayed with water or a weak acid solution to obtain phosphoric acid in solution. The furnace as herein shown and described is provided at its rear end with a gas outlet 36, leading off from above the slag pot, the upper wall of said outlet being formed by an extension of the top arch of the furnace and the lower wall 38 of which is formed of reinforced concrete, said lower wall having a lining 39 of fire brick. The extended portion of the top arch of the furnace constituting the upper wall of the gas outlet is supported by extended portions of the longitudinally extending I-beams 9, as more clearly shown in Fig. 6 and the bottom wall 38 of the gas outlet is supported by means of a transversely arranged I-beam 40, said I-beam being suspended by means of hangers 41 from the extended portions of the I-beams 9, as more clearly shown in said figure.

I prefer to provide the bottom wall 38 of the gas outlet with a cooling plate or unit 18^a as more clearly shown in Fig. 2, this plate or unit being removably inserted in a space or cell formed in the wall structure and held in place by means of yokes 42 similar to those heretofore described, the said yokes resting at their opposite ends respectively upon the angle beams 43 and 43^a, one of which is riveted directly to the transverse I-beam 40, and the other of which is embedded in the concrete wall.

A cooling medium such as water is fed to the various cooling plates or units of the furnace by means of pipe connections from a water main 44, Fig. 1, and the cooling medium is returned from the plates or units by means of pipe connections leading to a return pipe 45, said water feed and return pipes having separate inlet and outlet connections respectively with each water plate or unit and the main feed and return pipes being common to all of said connections. I prefer to provide the feed and return pipe connections leading to each cooling plate or unit with cut off valves as more clearly shown in Fig. 2 so that in case it is desired to remove either of the plates or units when the furnace is in operation or in case a break or leak occurs in any unit the cooling medium may be cut off from such unit without interfering with any of the other units. I also prefer to incorporate a flexible union or pipe section 46 preferably of a short rubber pipe section, in each feed and return con-

nection leading to the various cooling plates or units in order to facilitate removal and replacement of the various units and in order to lend safety to the structure, the flexible unions or pipe connections 46 constituting automatic blow outs in case the pressure in any one of the water cooled plates or units becomes so great as not to be taken care of by the feed and outlet pipes.

The material to be treated is fed to the furnace through a hopper 47 supported upon the top wall of the furnace, said hopper being disposed above an opening 48 leading into the furnace chamber directly above and centrally of the slag pot 29. The feed opening 48 is normally closed by means of a bell cover 49 in the usual way, all as more clearly shown in Fig. 2.

The material is heated by a pair of inclined or converging carbon electrodes 50 that extend through the arched top wall of the furnace so that their lower ends may be brought sufficiently close to bring about a proper electrical arc, the electrodes being adjustable vertically by any suitable means, not shown.

Experience has shown that these carbon electrodes deteriorate by the action thereon of the hot gases or fumes within the furnace, and in order to protect the same I propose to surround each electrode with a water cooled jacket, each jacket consisting of a pair of spaced metallic cylinders 51 one located within the other and connected at their ends by means of annular rings, and into each of which is led a pipe 52 for inlet of the cooling medium, and out of which leads an outlet pipe 53 for return of the cooling water, said inlet and outlet pipes being pipe connected respectively to the main feed pipe, and main return pipe as more clearly shown in Fig. 1. I prefer to lead the water inlet pipe of each cooling jacket thereinto longitudinally so that its outlet end terminates at a point slightly removed from the lower end or closure ring of the jacket so that the inflowing cooling water will enter the jacket at its hottest point. I also prefer to provide each inlet and outlet pipe with a cut off valve 54, and I also prefer to provide each inlet and outlet pipe with a flexible connection or pipe section 55, which flexible connections or pipe sections serve as safety blowouts, all as more clearly shown in Fig. 3.

In order to support and attach the electrode cooling jackets to the arch wall of the furnace, I provide each with an annular angle iron 56, one member of which is riveted to the jacket and the other member riveted to a supporting ring 57, riveted to the furnace arch.

It is desirable to prevent air from entering the furnace around the carbons as it has been found that this results in the car-

bons burning away, and to prevent the entrance of air through the annular space between the jacket and its carbon I provide a suitable packing to close the space. As more clearly shown in Fig. 5, the packing consists of an angle ring 58, and a flat annulus 59, between which is located one or more asbestos rope packing rings 6, which latter closely embrace the electrode and close the surrounding space. The packing means 10 is not attached to the electrode but is supported upon the outer end of its jacket, the electrode being free to move through the packing.

From the foregoing description taken in connection with the accompanying drawings, it will be seen that I have provided a furnace structure with novel and simple means for maintaining the furnace walls sufficiently cool to withstand the effects of the highly heated material within the furnace, and I have also provided means whereby the cooling plates or units may be easily and quickly removed in case any of the units 20 develop flaws or defects, the construction and arrangement of parts being such that removal of any unit may be effective without shutting down or cutting off the operation of the furnace, and without removing any part of the furnace superstructure or 30 tearing down any portion of the furnace wall.

While I have herein shown and described a preferred embodiment of the invention I do not wish to be understood as limiting myself to the precise details of construction herein shown and described, except as I may be limited by the terms of the appended claims, as I am aware that minor changes 40 or additions may be made to the structure without departing from the spirit of the invention.

What I claim is:—

1. In a furnace, a slag-pot having a 45 curved bottom and side walls, and having substantially vertical end walls, a plurality of substantially parallel bars extending longitudinally with the elements of said bottom and side walls, a plurality of substantially parallel bars at said end walls, said walls having cells or spaces formed therein between said bars, and a plurality of water-cooled units held in said spaces, said bars being partially embedded in said walls and 50 having flanges exposed on the outer sides of said walls, and means for engaging said flanges to secure the said water-cooled units in said cells.

2. In an electric furnace, a pair of cradle-beams, reinforced concrete supports secured at their opposite ends to said beams, and cooling plates or units located between and supported by said concrete supports.

3. In an electric furnace, a pair of spaced 65 cradle beams, spaced supports spanning said

beams and secured thereto at their opposite ends, and cooling plates or units located between said supports.

4. In an electric furnace, a pair of spaced cradle-beams, parallel supports arranged in spaced relation to each other and secured at their opposite ends to said beams, cooling plates or units located between said supports, and means for removably supporting said cooling plates or units. 70

5. In an electric furnace, a pair of spaced cradle-beams, parallel supports arranged in spaced relation to each other and secured at their opposite ends to said beams, cooling plates or units located between said supports, and means for removably supporting said cooling plates or units, said means resting upon the parallel supports. 75

6. In an electric furnace, a pair of spaced cradle-beams, a plurality of I-beams secured at their opposite ends to said cradle beams and arranged parallel to each other, cooling plates or units located between said I-beams, means for removably supporting said cooling plates or units, and means for supplying a cooling medium to the plates or units. 80

7. In an electric furnace, a pair of spaced cradle-beams, a plurality of metal beams secured at their opposite ends to said cradle beams and arranged parallel to each other, each of said parallel beams being partially embedded in concrete, cooling plates or units 90 removably supported between the concrete portions of said parallel beams, and means resting upon the unembedded portions of the concrete beams to removably support the cooling plates or units. 95

8. In an electric furnace, a pair of spaced cradle-beams, upright posts to which the opposite ends of said beams are secured, parallel supporting beams secured at their opposite ends to said cradle beams and arranged in spaced relation, cooling plates or units removably supported in the spaces between said parallel beams and removable 100 means supported by the parallel beams for holding the cooling plates or units in position. 105

9. In a furnace structure, a pair of spaced cradle-beams, upright supports secured to the opposite ends of said cradle-beams for supporting the latter, a plurality of spaced beams secured at their opposite ends to said cradle beams and arranged parallel to each other, separate cooling plates arranged between each pair of parallel beams, means for feeding cooling water to said cooling plates, a pair of arch supporting beams secured to the ends of the cradle beams, and a furnace arch supported by said arch supporting means. 110

10. In a furnace, a superstructure embodying cradle-beams, upright supports to which the opposite ends of said cradle beams are secured, spaced beams secured at their 115 120 125 ends.

- opposite ends to the cradle beams and arranged in parallel relation to each other, and longitudinally extending arch-supporting beams spanning the cradle beams and 5 secured thereto.
11. In a furnace, a superstructure embodying a pair of cradle-beams, upright beams to the upper ends of which the cradle beams are secured, parallel beams spanning 10 the cradle beams and secured thereto at their opposite ends, said parallel beams being arranged in spaced relation to each other, and longitudinally extending arch-supporting beams resting upon the ends of 15 the cradle beams and upright beams, and means for securing the latter named beams to the web portions of the arch supporting beams.
12. In a furnace, a superstructure embodying cradle-beams, upright beams to the upper ends of which the cradle beams are secured, parallel beams spanning the cradle beams and secured thereto at their opposite ends, arch-supporting beams secured to and 20 resting upon the opposite ends of the cradle-beams and the upper ends of the upright supports, and transverse beams forming parts of the front and rear walls of the furnace.
13. In an electric furnace, a metal superstructure, including a plurality of substantially parallel bars, walls supported thereby partially embedding said bars and having a plurality of water-cooled units embodied 25 therein between said bars, means for causing a cooling medium to flow through each cooling unit, a furnace arch supported by the superstructure, electrodes extending through said arch into the furnace, a slag-pot, and a 30 tap-spout leading from the slag-pot through a wall of the furnace.
14. In an electric furnace, a metal superstructure including a plurality of metal bars, walls partially embedding the same, and 35 having a plurality of water-cooled units embodied therein between said bars, means for removably supporting said units, means for causing a cooling medium to flow through each cooling unit, a furnace top wall supported by the superstructure, electrodes extending through said top wall into the furnace, a slag-pot, and a tap-spout leading 40 from the slag-pot through a wall of the furnace.
15. In a furnace of the character described having a slag-pot, a water-cooled slag-spout 45 leading from said pot, means for introducing cooling water into said spout, and means for discharging the outflowing cooling water across the outlet end of the spout. 60
16. In a furnace, a slag-pot, a water-cooled slag-spout leading from said pot, a chute below the spout, means for introducing cooling water into the spout, and means for discharging the outflowing cooling water across the outlet end of the spout and toward said chute. 65
17. In a furnace, a wall structure, a cooling plate or unit removably supported in a cell formed in the wall structure, and means for causing a cooling medium to flow through said plate or unit, said means embodying a flexible pipe section. 70
18. In a furnace of the character described, a furnace chamber, a metallic lining for the inner walls of the chamber, and a slag-pot within the chamber constructed of a cementitious mixture of slag and cement. 75
19. In a furnace of the character described, a furnace chamber, a series of metallic plates constituting a lining for the chamber, angle irons connecting the plates, and a slag-pot within the furnace, the said slag-pot being made from a composition of cement and a slag resulting from the reduction of phosphate rock and silica. 80
20. In a furnace, a furnace chamber and a slag-pot therefor, said pot being composed of a cementitious material made from cement and a slag which results from the melting of a mixture of phosphate rock and silica. 90
21. In a furnace, a wall, metal bars having flanges embedded in said wall and having flanges on the exterior of said wall, said wall having a plurality of cells or spaces between said bars, water-cooled units received in said cells, and means for holding said water-cooled units in said cells. 95
22. In a furnace in combination, a wall having a plurality of cells, cooling units adapted to be received in said cells, circulating pipes disposed near said wall, means for positively forcing said units forwardly into said cells, and flexible tubular connections connecting said cells with said pipes. 100
- In testimony whereof I have hereunto set my hand in presence of two subscribing witnesses. 105
